United States Patent Office

Des. 224,282

Patented July 18, 1972

224,282

FACE MASK

Thomas D. Candela, 34 E. 2nd St.,
New York, N.Y. 10003

Filed Nov. 2, 1970, Ser. No. 25,782

Term of patent 14 years

Int. Cl. D2—03

U.S. Cl. D2—234

FIG. 1.

FIG. 2.

FIG. 1 is a front perspective view of a face mask showing my new design;

FIG. 2 is a rear perspective view thereof.

The cross-hatching in FIGS. 1 and 2 is partially shown for convenience of illustration.

What I claim is:

The ornamental design for a face mask, substantially as shown and described.
